UNITED STATES PATENT OFFICE.

JOHN H. JEFFREY, OF CRESCENT CITY, CALIFORNIA, ASSIGNOR OF ONE-
THIRD TO HENRY ALBERT, OF SAME PLACE.

DEVICE FOR LIFTING GOODS FROM SHELVES.

SPECIFICATION forming part of Letters Patent No. 388,978, dated September 4, 1888.

Application filed March 5, 1888. Serial No. 266,269. (No model.)

To all whom it may concern:

Be it known that I, JOHN H. JEFFREY, of Crescent City, Del Norte county, State of California, have invented an Improvement in Devices for Lifting Goods from Shelves; and I hereby declare the following to be a full, clear, and exact description of the same.

My invention relates to a new and useful device or apparatus, the object of which is to facilitate the removal of goods from shelves; and my invention consists in the novel construction and arrangement of the gripping jaws or clamps, by which the goods are first engaged and drawn out from their place, the mechanism for operating the jaws to cause them to clamp the goods, the swinging table for receiving and bearing the weight of the goods, and the means for operating the table and holding it in position when the weight of the goods is imposed upon it, all of which, together with details of construction and arrangement and a slight modification of the gripping-jaws, I shall hereinafter fully describe.

The object of my invention is to provide an apparatus of simple construction and operation adapted for the purpose of removing bundles, packages, and goods of all kinds from shelves without having to use a ladder or mount to an elevated position.

Referring to the accompanying drawings, Figure 1 is a perspective view of my device. Fig. 2 is a detailed section of the fixed head B, showing the normal inclination of the lower jaw, C. Fig. 3 is a detail of collar-clamp G.

A is the handle or stock of the machine, made tubular, and having secured firmly upon its upper end the guide-head B, having a front section, b, hinged at b', and influenced by a spring, b'', to remain normally pressed out at an angle.

C is the lower clamp or jaw, which is secured to the hinged section b of the guide-head B, said jaw remaining normally at an upward inclination, as shown, due to the spring b'', acting behind the hinged section, to which it is attached.

D is the guide-head of the upper jaw, and E is said jaw or clamp, preferably made with an elongated head, e', so as to afford a proper bearing-surface on the goods. The head D

has secured to it the guide-rods d, which pass down loosely through sockets made in the lower guide-head, B, and into a collar, B', in which the lower ends are secured by a set-screw, w, and it has also secured to it a rod, d', which passes down completely through the tubular stock A of the device, and is secured in the lower end of a sliding sleeve, d'', fitted and adapted to move upon the lower end of the stock or handle. A spiral spring, d'', is fitted around the rod and serves to hold the upper jaw down in position on the goods.

The operation of the device as far as described is as follows: When in a normal condition, the upper jaw, E, is down to its limit, in proximity to the lower jaw, C, being held in this position by the spring d''. Now, by grasping the handle or stock A with one hand and the sliding sleeve d'' with the other, said sleeve may be pushed up on the stock, and thereby, through the internal rod, d', causing the upper guide-head, D, to move upwardly, carrying the upper jaw or clamp, E, with it until sufficient space is provided for the jaws C and E to slip onto the goods, the lower one going under them, while the upper one presses on their top. Then by releasing the sleeve d'' the spring d'' throws the upper jaw down upon the goods, which are then gripped between the two jaws. The upward inclination of the lower jaw, C, in the first instance provides for inserting it under the goods with facility, and said jaw moves down to a horizontal position under the weight of the goods until limited by the contact of the hinged section b with the main head B.

F is the table, preferably made of an open frame-work character, having a shank, f, which is hinged at f' to the main head B on the top of the stock A. Fitted loosely around the stock at a point below is a sliding collar, G, from which connecting-rods H extend upwardly and are connected with the sides of the hinged table F. A rod, I, is connected with the end of the table-shank at a point behind its pivotal center, and thence passes down through a suitable fixed guide, i, on the stock to within reach of the operating hand of the user. The collar G is provided on one side with hooks g, and the rod I has firmly secured to it a hinged or loosely-hanging eye-ring, i', which is adapt-

ed, when said rod is pulled down, to slip down by and engage up under the hooks *g*, so as to hold the two parts together.

The operation of the table is therefore as follows: When the goods have been pulled out from their resting-place by means of the jaws *C* and *E*, the table *F* is then elevated to the same horizontal plane as the lower jaw by means of pulling down on the rod *I*, so that the table then rests directly under and receives the goods. As the rod *I* moves down and the table moves up, it is obvious that the collar *G* on the stock *A* moves upward by means of the connecting-rods *H* until the ring *i* of the rod *I* engages the hooks *g* on the collar, whereupon, the two parts being held together, the table cannot move down, but is held in a proper horizontal position to sustain and carry the goods, which may then be lowered to within reach. I prefer to have the collar *G* made in the shape of a clamp, in two parts, hinged at one side at *g'*, and having its hooked ends separated normally; but when engaged by the ring *i* they pull together, whereby the collar is clamped on the stock, thus rendering additional security. In order to relieve the parts, the rod is freed by pulling it down and slipping its ring from the engagement with the hooks.

The table *F* may be provided on each side with hinged extensions *f'*, so as to increase its receiving capacity, said extensions being preferably made in the shape of wire frames.

Having thus described my invention, what I claim as new, and desire to secure by Letters Patent, is—

1. An apparatus for lifting goods from shelves, comprising a stock or handle, a lower jaw or clamp secured thereto, a sliding frame guided by the stock or handle, and an upper jaw or clamp secured to said frame, whereby it may be caused to approach to or be separated from the lower jaw, substantially as herein described.

2. An apparatus for removing goods from shelves, comprising a hollow or tubular handle or stock carrying a jaw or clamp at its upper end, a rod extending down through the tubular handle or stock, a sleeve fitted upon the lower end of the rod and sliding on the lower end of the stock or handle, and a jaw or clamp carried by the upper end of the rod, whereby it may be caused to approach or be separated from the lower jaw or clamp, substantially as herein described.

3. An apparatus for removing goods from shelves, comprising a tubular stock or handle, a jaw or clamp secured to its top, a rod passing down through the tubular stock or handle, a sliding sleeve on the lower end of the handle and connected with the rod, whereby the rod may be moved up, a spring around said rod for moving it down, and a jaw or clamp carried by the rod above the jaw or clamp, substantially as herein described.

4. An apparatus for removing goods from shelves, comprising a stock or handle having

at its upper end a fixed head, with the hinged section *b*, and the spring for throwing said section outwardly at an angle, a jaw or clamp carried by the hinged section at an upward inclination, a jaw or clamp above, and a sliding frame for operating said upper jaw or clamp, substantially as herein described.

5. An apparatus for removing goods from shelves, comprising a tubular stock or handle having on its upper end a fixed guide-head, a jaw or clamp carried by said head, a guide-head above, a jaw or clamp carried by said upper guide-head, a guide-frame carrying said head and passing downwardly through the lower guide-head, a rod secured to the upper guide-head and passing through the tubular stock or handle, a sleeve on the lower end of the rod and fitted and adapted to slide upon the lower end of the stock or handle, and a spring around the rod for returning it to position, substantially as herein described.

6. In an apparatus for removing goods from shelves, a stock or handle and a table hinged thereto, in combination with a pull-rod attached to the table behind its hinge, whereby it is raised to a horizontal position, a sliding collar on the stock or handle, rods connecting said collar with the table in front of its hinge, and a connection comprising the hooks *g* between the pull-rod and the sliding collar, whereby the table is held in a horizontal position, substantially as herein described.

7. In an apparatus for removing goods from shelves, a stock or handle and a table hinged thereto, in combination with a pull-rod attached to the table at one side of its hinge, whereby it may be raised to a horizontal position, a sliding collar on the stock or handle, rods connecting said collar with the table on the other side of its hinge, hooks on the collar, and a ring on the pull-rod, whereby the engagement is effected and the table held in a horizontal position, substantially as herein described.

8. In an apparatus for removing goods from shelves, the combination of a lower jaw or clamp and an upper jaw or clamp adjustable to and from each other, whereby the goods may be gripped between them, and a hinged table arranged to be brought up to the level of the lower jaw to receive the weight of the goods, substantially as herein described.

9. An apparatus for removing goods from shelves, comprising a stock or handle having a jaw on its top, a sliding frame having a jaw on its top above, a table hinged to the stock or handle, and a pull-rod for raising the table to the horizontal plane of the lower jaw, substantially as herein described.

10. An apparatus for removing goods from shelves, comprising the stock or handle having a jaw on its top, a sliding frame having a jaw above the first-named jaw, a table hinged to the stock or handle, a pull-rod connected with the table on one side of its pivotal center, a clamp-collar sliding on the stock or handle, and rods connecting it with the table on the

other side of its pivotal center, separated hooks on the collar, and an eye-ring on the pull-rod for engaging the hooks to clamp the collar on the stock or handle and hold the table in a 5 horizontal position, substantially as herein described.

11. An apparatus for removing goods from shelves, comprising the tubular stock or handle having a jaw on its top, a sliding frame 10 having a jaw above the first-named jaw, a rod secured to said upper jaw and passing downwardly through the stock or handle, a sleeve on its lower end sliding on the lower end of

the stock or handle, a table hinged to the upper end of the stock or handle, a pull-rod connected with one end of the table and a sliding collar connected with the other end, and the hook-and-eye connection between the collar and the pull-rod, all arranged and adapted to operate substantially as herein described. 15 20

In witness whereof I have hereunto set my hand.
